UNITED STATES PATENT OFFICE.

ANDREW LITTLE, OF NEW YORK, N. Y.

DESIGN FOR A FONT OF PRINTING-TYPE.

SPECIFICATION forming part of Design No. 12,941, dated May 23, 1882.

Application filed March 21, 1882. Term of patent 7 years.

To all whom it may concern:

Be it known that I, ANDREW LITTLE, of the city, county, and State of New York, have invented and produced a new and original Design for a Font of Printing-Type, of which the following is a specification.

The nature of my design is clearly shown in the accompanying typographic impression, to which reference is made; and it consists of an ornated letter, the up and down portions of which are composed of the heavy lines with spaces between them, shaded upon the left by a lighter line, concaved as shown.

In the letters A, M, N, and X the triangular terminations are found at the base on the

left, and also in the C E F L S U and Y G K N T V W X Z and symbol & upon the right. The faces of the letters are further ornamented by the heavy figures following the configuration of the outline.

In the figures and symbols the character of the design is preserved as shown.

Having now set forth my invention, what I claim as new is—

The design for a font of printing type, as shown and described.

ANDREW LITTLE.

WILLIAM V. H. HICKS,
A. SIDNEY DOANE.
